of New York

Application May 29, 1944, Serial No. 113,780

Term of patent 7 years

(Cl. D87—2)

To all whom it may concern:

Be it known that we, John De Pasquale and Alexander Westerman, citizens of the United States, residing at Brooklyn, in the county of Kings, city and State of New York, have invented a new, original, and ornamental Design for a Frame for a Handbag or Similar Article, of which the following is a specification, reference being had to the accompanying drawing, forming part thereof.

In the drawing:

Fig. 1 is a front elevational view of a frame for a handbag or similar article showing our new design, the dominant feature of the design being shown in full lines.

Fig. 2 is a top plan view thereof.

We claim:

The ornamental design for a frame for a handbag or similar article, substantially as shown and described.

JOHN DE PASQUALE.
ALEXANDER WESTERMAN.
